UNITED STATES PATENT OFFICE.

JOHN E. SCHAEFER, OF BUFFALO, MINNESOTA.

DESIGN FOR AN AUTOMOBILE TOP.

Application filed November 12, 1926. Serial No. 19,697. Term of patent 14 years.

To all whom it may concern:

Be it known that I, JOHN E. SCHAEFER, a citizen of the United States, residing at Buffalo, in the county of Wright and State of Minnesota, have invented a certain new, original, and ornamental Design for Automobile Tops, of which the following is a specification.

Fig. 1 is a side elevation of an automobile having a top or roof of my new design.

Fig. 2 is a top or plan view of Fig. 1.

I claim:

The ornamental design for an automobile top as shown.

JOHN E. SCHAEFER.
